UNITED STATES PATENT OFFICE

JOHN A. HOLSMAN, OF DES MOINES, IOWA

CIGARETTE JACKET

Application filed May 9, 1930. Serial No. 451,043.

The object of my invention is to provide a jacket of simple and inexpensive construction, which can be conveniently and easily placed on a cigarette for affording means whereby the cigarette may be grasped without the likelihood of staining the fingers or the necessity of directly grasping the cigarette.

With this and other objects in view my invention consists in the construction, arrangement and combination of the device, whereby the objects contemplated are attained, as hereinafter more fully set forth, pointed out in my claim, and illustrated in the accompanying drawing, in which:—

Figure 1 is a perspective view of a cigarette having thereon a jacket embodying my invention.

Figure 2 is a detailed sectional view taken on the line 2—2 of Figure 1.

Figures 3, 4 and 5 are similar views illustrating the different forms in which the invention may be made.

Figure 6 is a perspective view of one of the modified forms of my jacket.

It is well known that some people, particularly women, have compunctions against holding a cigarette in the fingers on account of the odor and stain which may be imparted.

Ordinary cigarette holders are expensive enough that the owner does not want to throw them away and they retain a stagnant odor to the garments or bag in which they are carried.

My purpose, therefore, is to provide a jacket for a cigarette which can be placed on the cigarette so that the user can grasp the jacket instead of the cigarette, which jacket is so inexpensive that after one use it can be thrown away.

In Figures 1 and 2 I have shown such a jacket indicated at A, made in the form of a cylinder of any suitable material, such for instance as thin paper. It will, of course, be understood that the material used might be cardboard, asbestos, metal, or any composition suitable for the purpose.

In the form of the invention shown in Figures 1 and 2, holes are pricked in the jacket A as indicated at 10.

The holes are perforated from the outside and it will be understood that this manner of making them causes small tongues 12 to be forced inwardly. These tongues serve as means which may engage the cigarette and hold the body of the jacket spaced from the cigarette.

At the same time the fingers 12 frictionally grip the cigarette in such a way that the jacket will be snugly and firmly held thereon.

I prefer to slightly flare one end of the jacket A as indicated at 14 in Figure 1 so that the end of the cigarette may be conveniently inserted into the jacket. This makes it possible to place the jackets in a box with the flared ends of the jacket at the open end of the box so that a cigarette can be inserted into one of the jackets and upon withdrawal of the cigarette the jacket will adhere thereto.

In Figures 3, 4 and 5 I have shown different shapes which may be given to the jacket.

It will, of course, be understood that the jacket could be smooth, but I preferably prefer to prick the holes as shown in Figure 1, or to provide regular indentations as shown in the jacket B of Figure 3 at 16.

In Figure 4 I have shown a pleated jacket C.

In Figure 5 a jacket D longitudinally corrugated is shown.

Greater variety of shapes could be employed.

The material used may be of inflammable material, or of material which will not readily burn.

It will be obvious that the tongues 12, or the indentations, or the corrugations, or the pleats 16, may be provided for the entire length of the jacket, or only at the ends, or in circumferential belts, or as may be desired.

It is obvious also that the corrugations or pleats might extend circumferentially instead of lengthwise of the jacket.

The jackets may be made in colors if desired.

Where they are made of stiff enough material, the cylinder may be split and formed

with a longitudinal slot 20 as indicated in Figures 5 and 6, or without the slots.

The length, shape, size and material may be changed to suit the taste of the manufacturer and the price of the finished product; keeping in mind, of course, that I prefer such product as can be made at a cost low enough so that the jackets may be sold at a low price and may be thrown away after one use.

10 Where such a jacket is employed the user of cigarettes will not acquire the stain or odor which are so objectionable.

I claim as my invention:

15 A temporary jacket for cigarettes comprising a light thin cylinder of slightly resilient flexible material having portions impressed for resiliently engaging the cigarette at a large number of points, the impressed 20 portions extending radially inwardly and the parts being so arranged that the jacket may be readily moved lengthwise in either direction on the cigarette or may be grasped by the fingers and pressed against the cigarette so that the cigarette will not move 25 therein.

Des Moines, Iowa, April 12, 1930.

JOHN A. HOLSMAN.
